PROCESS AND APPARATUS FOR CONTINUOUS TREATMENT
OF HYDROCARBON OIL WITH A METALLIC HALIDE

Filed Nov. 27, 1926

UNITED STATES PATENT OFFICE

RICHARD W. HANNA, OF PIEDMONT, CALIFORNIA, ASSIGNOR TO STANDARD OIL COMPANY OF CALIFORNIA, OF SAN FRANCISCO, CALIFORNIA, A CORPORATION OF DELAWARE

PROCESS AND APPARATUS FOR CONTINUOUS TREATMENT OF HYDROCARBON OIL WITH A METALLIC HALIDE

Application filed November 27, 1926. Serial No. 151,165.

This invention relates to the treatment of hydrocarbon oils, such as petroleum oil, shale oil, or oils derived from coal or similar sources, with a metallic halide such as aluminum chloride, and refers particularly to a continuous process of treating the hydrocarbon oil with a metallic halide.

In the conventional process of treating hydrocarbon oils with aluminum chloride, the hydrocarbon oils are agitated together in batch lots with aluminum chloride in a reaction chamber in which heat is supplied to the chamber walls to maintain the desired reaction temperature. In such a process, considerable difficulty is experienced due to the necessity of employing a mechanical agitator in the reaction chamber. Moreover, the addition of the greater portion of the heat to the admixture in the reaction chamber results in unnecessarily large tar or coke formations and in a poor efficiency of heat transfer. Furthermore, the conducting of the process in batch lots results in a low yield of product from a given size apparatus.

An object of the present invention is to provide a process of treating hydrocarbon oil with aluminum chloride in which the hydrocarbon oil and aluminum chloride may be continuously agitated together with a continuous conversion of hydrocarbon oil to low boiling point oil or naphtha and the continuous removal of residual aluminum chloride.

Another object of the present invention is to provide a continuous apparatus for treating hydrocarbon oil with aluminum chloride in which an agitation of the materials may be effected by circulation of liquid from the reaction chamber back into the reaction chamber entering in the form of jets so that the liquid undergoing treatment serves as an agitating means for the mixture. By this method, the process of the present invention eliminates the problems encountered in the processes employing a mechanical agitation of aluminum chloride and hydrocarbon oil

together or when the oil agitation is combined with mechanical agitation substantially simplifies and reduces the mechanical agitating problems.

Another object of the present invention is to provide a process in which a part, preferably the major part, or final heating of the hydrocarbon oil is conducted in a heating zone separate from the reaction chamber by a continuous circulation of hydrocarbon oil or the liquid admixture from the reaction chamber through said heating zone and back into said agitating chamber. In this manner, excessive formation of carbon or coke and high heat losses are avoided.

Another object of the invention is to provide a process in which a single stream of liquid may be withdrawn from a source of bulk supply of hydrocarbon oil and aluminum chloride and circulated through a heating zone and back into said bulk supply entering in the form of agitating jets. The necessary heat for the reaction is applied largely separate from the agitation chamber and the heated stream serves as agitating means.

Another object of the present invention is to provide a continuous process of treating hydrocarbon oil with aluminum chloride in which there may be circulated from the bulk supply of said materials a liquid which in its circulating path has separated therefrom any aluminum chloride compound so that only a substantially clean stream of hydrocarbon oil passes through the heating zone.

Various further objects and advantages of the present invention will be understood from a description of a preferred form of process and apparatus embodying the invention. For this purpose, reference is made to the accompanying drawing in which there is illustrated a preferred example of an apparatus embodying the invention, in which apparatus the preferred process embodying the invention may be carried out.

The drawing represents a diagrammatic view mainly in elevation and partially in vertical section of the apparatus.

Referring to the drawing, the reaction chamber in which the bulk supply of materials is maintained is generally indicated at 2. Said reaction chamber is preferably an incumbent cylindrical tank. 3 indicates a storage vessel or other suitable source of hydrocarbon oil. The storage vessel 3 is indicated as provided with a line 4 including a pump 5 by which the hydrocarbon oil may be withdrawn from the storage vessel 3 and passed into the reaction chamber 2. The fresh hydrocarbon oil may be directly introduced into the said reaction chamber or into a vapor line 6 leading from said reaction chamber. Preferably the hydrocarbon oil line 4 is connected with the lines 7 and 8, the line 7 leading to the upper portion of a dephlegmator or reflux tower 9 connected with the vapor line 6 and the line 8 leading to a circulating line 10. The circulating line 10 is connected with the reaction chamber at one end, as indicated at 11, and includes a pump 12 by which liquid may be withdrawn from the reaction chamber and forcibly circulated through the heating zone and back into the chamber. Preferably the heating zone comprises a coil 13 positioned within a furnace 14. The circulating line 10 also preferably includes a trap 15 between the pump 12 and coil 13 by which any aluminum chloride or tarry residue may be separated from the circulating stream of liquid, said trap being indicated as preferably provided with the central baffle 16 having openings at its top and bottom and with a line 17 leading back to the reaction chamber 2 for return of separated tar or aluminum chloride to the reaction chamber. The line 8, introducing part of the feed oil into the system, preferably connects with the circulating line 10 between the trap 15 and heating coil 13.

The trap 15 operates as follows: The oil which enters the trap rises upwardly through the trap and heats the baffle 16. This causes the tarry particles to be impounded against the baffle while the liquid particles flow around the baffle and out through the upper outlet of the trap. The tarry particles impounded against the baffle collect and drip back to the bottom of the trap and are forced through the lower opening of the trap back into the chamber 2.

The circulating line 10 is indicated as terminating within the reaction chamber 2 in a plurality of jet pipes 18 positioned near the bottom of the reaction chamber and spaced apart throughout the bottom of the reaction chamber so that the oil entering the reaction chamber from the circulating line 10 is distributed through the reaction chamber in a number of high velocity jets. The end 11 of the circulating line 10 is preferably

connected within the still to a line 19 which leads to a position under the vapor line 6 and is there connected with a pan 20 for catching reflux oils and feed oil from the vapor line 6.

The reflux tower 9 is indicated as connected with a vapor line 21 which leads to a condenser 22 from which a line 23 carries condensed oil to a receiving tank 24 for the produced low boiling point oil or naphtha. Said receiver 24 is indicated as provided with a valved gas vent 25 by which pressure, if desired, may be imposed upon the system. The tank 24 also may be connected with a line 26 for discharge of the produced low boiling point oil or naphtha.

The reaction chamber 2 is also preferably provided with a charger 27 by which anhydrous aluminum chloride may be intermittently or continuously introduced into the reaction chamber 2 while the said chamber is under pressure. For this purpose, the charger 27 includes the two spaced apart valves 28 and 29, and the hopper 30. In certain cases, it may be desirable to introduce the aluminum chloride continuously into the reaction chamber 2 in a liquid form, for example, by admixing the aluminum chloride with some hydrocarbon oil and for this purpose, the charger 27 is indicated as connected with a line 31. The reaction chamber 2 is also indicated as preferably connected with a residual draw off line 32 connected with a cooler 33 and hence to a residual tank 34 having the oil withdrawal line 35 and the tar withdrawal line 36.

The process as conducted in the apparatus thus described is preferably as follows: In starting the apparatus, the hydrocarbon oil in proper quantity is charged into the reaction chamber 2 and is then circulated from said reaction chamber 2 through circulating line 10 and the heating zone back into said chamber until the desired reaction temperature is reached. When the desired reaction temperature is reached, aluminum chloride or equivalent metallic halide is added to the hydrocarbon oil and the process is then continued in a continuous manner by continuously or intermittently adding the requisite aluminum chloride and continuously passing further fresh oil to the system.

While the process may operate employing any desired hydrocarbon oil, an example of a suitable oil responding particularly well to the process is gas oil fractions of petroleum oil such, for example, as have a Beaumé gravity of 25° and derived from California or asphaltic base crude oil. The quantity of aluminum chloride added to the oil will vary largely with the character of oil to be treated and the temperature of treatment, and the character of product desired. When desiring to produce U. S. motor grade gasoline from the particular oil referred to, I generally prefer to employ between 5 and 10 per

cent. by weight of aluminum chloride. The temperature of the reaction may also be varied through considerable range but is generally between 550° and 650° F.

Preferably the materials within the reaction chamber 2 are maintained under a pressure of evolved vapors which is substantially above atmospheric. For example, a pressure of 15 pounds per square inch gage is the preferred operating pressure.

During the continuous operation of the process, vapors of produced low boiling point oil or naphtha are continuously passed out vapor line 6 together with some higher boiling point oil and some aluminum chloride. Said vapors are cooled within the dephlegmator 9 to a discharge temperature suitable for condensing therefrom all fractions but those desirable in the finished naphtha. For this purpose, the discharge temperature is generally held between 300° and 360° F. The cooling of the vapors is preferably accomplished by passing a portion of the feed oil through line 7 into the uprising vapors whereby the cooling of the vapors also results in heating this portion of the fresh oil. This portion of the feed oil together with any reflux or condensed heavier oils pass through the vapor line 6 into the reaction chamber 2 and are there caught in the pan 20 and part at least thereof is circulated or recirculated from the bulk supply of materials within said chamber through the heating coil 13 and back into said chamber. In the process, part of the bulk supply in the chamber 2 is circulated from the chamber to the line 10 and heating zone back into the chamber, by reason of the fact that a part of the supply in chamber 2 is continuously vaporized and entrained with vapors passing out the line 6, where the dephlegmator 9 returns the same to the pan 20, from whence it passes to the line 10. Within the trap 15 any portion of the aluminum chloride or tar in the circulating line 10 is separated therefrom and preferably continuously passed again to the reaction chamber 2. There is also added to the stream of materials being circulated in line 10 a part of the feed oil to the system and said circulated oil and fresh feed oil passes from the circulating line 10 under high velocity from jets 18 into the bulk supply of materials within the reaction chamber 2. The introduction of said liquid in the form of jets into the reaction chamber 2 thoroughly agitates and commingles the hydrocarbon oil with the aluminum chloride, thus overcoming the agitation problems encountered in the normal processes.

Preferably during the process, aluminum chloride residue is intimately or continuously withdrawn through line 32, passed through cooler 33, and hence into a receiver or residuum tank 34. In said tank 34, any oil entrained in the residue is separated and

withdrawn from line 35 while the residuum is withdrawn through line 36.

While the particular form of the invention herein described is well adapted to carry out the objects of the invention, numerous modifications may be made and the invention is of the scope set forth in the appended claims.

I claim:

1. A process of treating hydrocarbon oil with anhydrous metallic halide which comprises maintaining a bulk supply of hydrocarbon oil and metallic halide at a conversion temperature and undergoing a decomposing reaction in a reaction chamber, passing the evolved vapors therefrom to a reflux tower, withdrawing reflux liquid from said reflux tower and circulating a part of said liquid through a heating zone and back into said reaction chamber, separating metallic halide sludge from the circulating liquid, and passing the metallic halide sludge back into said reaction chamber without passing through said heating zone. 75

2. An apparatus for treating hydrocarbon oils with anhydrous metallic halide in order to decompose the hydrocarbon oils into lower boiling point oils comprising a reaction chamber, a reflux tower operatively connected with said reaction chamber, a circulating line leading from said reflux tower through a heating zone and back into said reaction chamber, a separator operative for separating metallic halide sludge from the liquid circulating in said line, and a by-pass line for passing the metallic halide sludge thus separated back into said reaction chamber without passing through said heating zone. 90

3. A process of treating hydrocarbon oils with metallic halide which comprises continuously maintaining a bulk supply of hydrocarbon oil and metallic halide at a conversion temperature, continuously passing evolved vapors from said bulk supply to a reflux zone, continuously circulating reflux liquid from said reflux zone through a cleansing and separating zone to remove halide contained therein, and then passing the cleansed liquid through a heating zone into said bulk supply, the liquid thus circulated and cleansed being caused to continuously agitate said bulk supply, and continuously passing fresh oil into said bulk supply while diverting a portion of said oil to said reflux tower. 105

4. An apparatus for treating hydrocarbon oils with anhydrous metallic halide for decomposing the hydrocarbon oils into lower boiling point oils, comprising a reaction chamber, a reflux tower operatively connected with said reaction chamber, a circulating line leading from said reflux tower through a heating zone and back into said reaction chamber, said line terminating in a plurality of jetting means within said reaction chamber. 125

ber whereby liquid from said line is caused to agitate the contents of said reaction chamber, separating means for separating metallic halide sludge from the liquid circulating in said line positioned in said line between said reflux tower, a heating zone, and a bypass line for passing the metallic halide sludge thus separated back into said reaction chamber without passing through said heating zone.

5 10 Signed at San Francisco, California, this 16th day of November, 1926.
